UNITED STATES PATENT OFFICE.

HELEN J. CUMMINGS, OF CLEVELAND, OHIO, ASSIGNOR TO GENERAL ELECTRIC COMPANY, A CORPORATION OF NEW YORK.

DESIGN FOR A LAMP SHADE OR SIMILAR ARTICLE.

Application filed November 9, 1923. Serial No. 7,726. Term of patent 3½ years.

To all whom it may concern:

Be it known that I, HELEN J. CUMMINGS, a citizen of the United States, residing at Cleveland, in the county of Cuyahoga, State of Ohio, have invented a new, original, and ornamental Design for a Lamp Shade or Similar Article, of which the following is a specification, reference being had to the accompanying drawing, forming a part thereof.

The figure in an elevational view of a lamp shade comprising my invention.

I claim:

The ornamental design for a lamp shade or similar article, substantially as shown.

In witness whereof, I have hereunto set by hand this 6th day of November, 1923.

HELEN J. CUMMINGS.
